1

This invention relates to improving the stability of hydrocarbons and has particular reference to stabilized petroleum distillates, such as cracked gasoline containing unsaturated hydrocarbons.

As is known, gasoline obtained by cracking so-called heavy petroleum oils considerably changes its properties when kept in storage. Such changes affect the value of gasoline as a motor fuel and often render it entirely unsuitable for this purpose. In the following disclosure, all substances which stabilize reformed (cracked) gasoline will be called, for brevity's sake, inhibitors.

In the past, it has been recommended to add various inhibitors to unstable gasolines to improve their storage stability. Among the active inhibitors are particularly the alkylated phenols, aromatic amines and hydroxy amines, etc. While many of these inhibitors have a limited beneficial effect upon the stability of cracked gasolines, unduly large amounts of the inhibitors are sometimes required in order to obtain satisfactory stabilization, thus leading to the formation of engine deposits when the inhibited gasoline is used as fuel. Again, some of the proposed inhibitors have only a limited effect, irrespective of the amounts added to gasoline. In order to be outstanding, an inhibitor must be capable of stabilizing gasoline satisfactorily when present even in extremely small amounts.

It is an object of this invention to provide an outstanding class of gasoline inhibitors. It is another object of this invention to provide gasolines of exceptional storage stability. It is a further object of this invention to provide gasoline compositions having little tendency to form gum deposits. It is a fourth object of this invention to provide gasoline compositions having exceptional color stability. Other objects will become evident during the following disclosure.

Now, in accordance with this invention, it has been discovered that one class of inhibitors is superior to any others tested for the stabilization of cracked gasoline. These inhibitors are substituted dihydroxydiphenyls having the general configuration

wherein one R attached to each phenyl radical is any alkyl group, preferably an alkyl group having one to twelve carbon atoms, and each remaining R is a primary or secondary alkyl group.

Inhibitors having the above configuration are 3,5,3',5'-tetraalkyl dihydroxydiphenyls. They may be prepared by oxidation of one or more

alkylated phenols having alkyl groups attached to the two carbon atoms adjacent to that linking the phenolic hydroxyl group. Such alkylated phenols have the general configuration

5

2

wherein one R is any alkyl group and the other R is a primary or secondary alkyl group. Thus, the resulting alkylated dihydroxy-diphenyls may have the following typical configurations

15 1.

2.

20 3.

4.

5.

6.

wherein R₁, R₂, R₃ and R₄ are dissimilar alkyl groups and each phenyl radical contains at least one primary or secondary alkyl group.

The symmetrical type of inhibitors represented by Formula 1 above may be prepared by the oxidation of a single 2,6-dialkyl phenol wherein the alkyl groups are identical groups of primary or secondary configuration. Such diphenyl derivatives include 3,5,3',5'-tetramethyl-4,4'-dihydroxydiphenyl, 3,5,3',5' - tetraethyl - 4,4' - dihydroxydiphenyl, 3,5,3',5' - tetrapropyl - 4,4' - dihydroxydiphenyl, 3,5,3',5' - tetraamyl - 4,4' - dihydroxydiphenyl, 3,5,3',5' - tetrahexyl - 4,4' - dihydroxydiphenyl, 3,5,3',5' - tetraheptyl-4,4' - dihydroxydiphenyl, 3,5,3',5' - tetraoctyl-4,4' - dihydroxydiphenyl, 3,5,3',5' - tetranonyl - 4,4' - dihydroxydiphenyl, 3,5,3',5' - tetradecyl - 4,4' - dihydroxydiphenyl, 3,5,3',5' - tetradodecyl - 4,4' - dihydroxydiphenyl, etc.

Inhibitors having the general configuration of Formula 2 above may be prepared by the simultaneous oxidation of two 2,6-dialkyl phenols, each having at least one alkyl group of primary or secondary configuration, one of which phenols has dissimilar alkyl groups, the other of which has alkyl groups which are both identical with one of said groups of the first phenol. This type of

Inhibitor is illustrated by such diphenyl derivatives as

3,5',5'-trimethyl-5-ethyl-4,4'-dihydroxydiphenyl,
3,3',5'-triethyl-5-methyl-4,4'-dihydroxydiphenyl,
3,5,3'-tripropyl-5'-butyl-4,4'-dihydroxydiphenyl,
3,5,3'-tributyl-5-methyl-4,4'-dihydroxydiphenyl,
5,3',5'-triamyl - 3 - isopropyl - 4,4' - dihydroxy-
diphenyl,
5,3',5'-trihexyl-3-amyl-4,4'-dihydroxydiphenyl,
3,5,3'-triheptyl-5-ethyl-4,4'-dihydroxydiphenyl,
3,5,3'-trioctyl-5'-butyl-4,4'-dihydroxydiphenyl,
3,5,5'-trinonyl-3'-heptyl-4,4'-dihydroxydiphenyl,
3,5,3'-tridecyl-5'-methyl-4,4'-dihydroxydiphenyl,
3,5,5'-tridodecyl-3'-ethyl-4,4'-dihydroxydiphenyl,
etc.

Formula 3, given above represents alkylated dihydroxydiphenyls which may be prepared by the simultaneous oxidation of two symmetrical 2,6-dialkyl phenols the alkyl groups of one phenol differing from those of the other phenol but each phenol having at least one alkyl group of primary or secondary configuration. Inhibitors having this type of configuration include

3,5-dimethyl-3',5'-diethyl-4,4'-dihydroxydiphenyl,
3,5-diethyl-3',5'-dipropyl-4,4'-dihydroxydiphenyl,
3,5-diisopropyl-3',5'-dimethyl-4,4' - dihydroxydiphenyl,
3,5-di-tert-butyl-3',5'-diethyl-4,4' - dihydroxydiphenyl,
3,5-di-n-amyl-3',5' - dibutyl - 4,4' - dihydroxydiphenyl,
3,5-dihexyl-3',5'-diisopropyl - 4,4' - dihydroxydiphenyl,
3,5-diheptyl-3',5'-diethyl-4,4'-dihydroxydiphenyl,
3,5-dioctyl-3',5'-diamyl-4,4'-dihydroxydiphenyl,
3,5-dinonyl - 3',5' - dimethyl - 4,4' - dihydroxydiphenyl,
3,5-didecyl-3',5'-dimethyl-4,4'-dihydroxydiphenyl,
3,5-didodecyl - 3',5' - diethyl - 4,4' - dihydroxydiphenyl, etc.

Another suitable type of inhibitors, having the general Formula 4, given above, may be prepared by the simultaneous oxidation of two different 2,6-dialkylphenols, one of which is symmetrical, the other of which is unsymmetrical, the alkyl groups of the first differing from those of the second but each phenol having at least one alkyl group of primary or secondary configuration. Representatives of this configuration are

3,5-dimethyl-3'-ethyl-5'-propyl-4,4' - dihydroxydiphenyl,
3,5-diethyl-3'-methyl-5'-propyl-4,4' - dihydroxydiphenyl,
3,5-diisopropyl-3'-methyl-5' - ethyl - 4,4' - dihydroxydiphenyl,
3,5-dibutyl-3'-methyl-5'-propyl-4,4' - dihydroxydiphenyl,

3,5-diamyl-3'-ethyl-5'-methyl-4,4'-dihydroxydiphenyl,
3,5-dihexyl-3'-methyl-5' - isopropyl - 4,4' - dihydroxydiphenyl,
5 3,5-dihexyl-3'-methyl-5' - ethyl-4,4' - dihydroxydiphenyl,
3,5-dioctyl-3'-ethyl-5'-heptyl-4,4' - dihydroxydiphenyl,
3,5-dinonyl-3'-methyl-5' - ethyl-4,4' - dihydroxydiphenyl,
10 3,5-didecyl-3'-methyl-5' - methyl - 4,4' - dihydroxydiphenyl,
3,5-didodecyl-3'-methyl - 5' - nonyl - 4,4' - dihydroxydiphenyl, etc.

15 Another preferred configuration of the subject gasoline inhibitors is that of Formula 5, given hereinbefore. Inhibitors of this category may be prepared by the oxidation of a single unsymmetrical 3,5-dialkyl phenol having at least one alkyl group of primary or secondary configuration. Inhibitors of this type are

3,3'-dimethyl-5,5'-diethyl-4,4'-dihydroxydiphenyl,
25 3,3'-diethyl-5,5'-diisopropyl - 4,4' - dihydroxydiphenyl,
3,3'-dipropyl-5,5' - dimethyl - 4,4' - dihydroxydiphenyl,
3,3'-di-tert-butyl-5,5'-diethyl-4,4' - dihydroxydiphenyl,
30 3,3'-diamyl-5,5'-dimethyl-4,4'-dihydroxydiphenyl,
3,3-dihexyl-5,5' - diisopropyl - 4,4' - dihydroxydiphenyl,
3,3'-diheptyl-5,5'-diethyl-4,4'-dihydroxydiphenyl,
3,3'-dioctyl-5,5'-dibutyl-4,4'-dihydroxydiphenyl,
3,3'-dinonyl-5,5'-di-sec-butyl-4,4' - dihydroxydiphenyl,
40 3,3'-didecyl-5,5'-dimethyl-4,4' - dihydroxydiphenyl,
3,3'-didecyl-5,5'-diamyl-4,4' - dihydroxydiphenyl, etc.

Another class of the subject inhibitors is represented by the general Formula 6, given hereinbefore, and includes such inhibitors as 3-methyl-5-ethyl-3'-isopropyl-5'-butyl-4,4' - dihydroxydiphenyl, etc. Mixtures of the above inhibitors may be used.

50 When used in the average cracked gasolines, inhibitors having the general configuration of the present invention are effective in relatively small amounts, usually from about 0.001% to about 0.1% by weight.

EXAMPLE I
For matters of comparison, and to show the critical nature of the configuration of the inhibitors of the present invention, the effectiveness of the various phenyl derivatives listed below are related to that of cresylic acid, a well-known gasoline inhibitor. The inhibitors were added to cracked gasoline and tested by the standard oxygen bomb test.

Table 1

Inhibitor	Inhibitor concentration required to increase the Induction Period of the gasoline 4 hours	Effectiveness Relative to Cresylic Acid
Cresylic acids.		
3,3',5,5'-tetramethyl-4,4'-dihydroxydiphenyl	17.0	16.2
3,3'-dimethyl-4,4'-dihydroxydiphenyl	1.05	5.6
4,4'-dihydroxydiphenyl	3.0	0.91
3,3',5,5'-tetramethoxy-4,4'-dihydroxydiphenyl	15.6	3.3
	6.1	

5

EXAMPLE II

A cracked gasoline of different origin from that used in Example 1 was inhibited with the various materials listed in Table 2. The stability of each blend was determined by the oxygen bomb test, with cresylic acids being used as the reference inhibitor.

Table 2

Inhibitor	Inhibitor Concentration required to increase the Induction Period of the Gasoline 4 hours	Effectiveness Relative to Cresylic Acids
Cresylic Acids	18	1.0
3,3'-5,5'-tetramethyl-4,4'-dihydroxydiphenyl	3	6.0
3,3'-dimethyl-5,5'-di-tert-butyl-4,4'-dihydroxydiphenyl	4.2	4.3
3,3'-diethyl-5,5'-di-tert-butyl-4,4'-dihydroxydiphenyl	4.8	3.8
3,3'-5,5'-tetra-tert-amyl-4,4'-dihydroxydiphenyl	21.5	0.85

While the subject inhibitors have been found to be particularly suitable for use in cracked gasoline, they also constitute satisfactory stabilizing agents for use in organic compounds in general; particularly other petroleum products including aviation gasoline, turbine oils, lubricating oils, hydrocarbons, hydrocarbon polymers, and other oleaginous materials, such as benzene, turpentine, corn oil, cottonseed oil; animal oils such as neat's-foot oil and lanolin; fish oils such as sperm oils; synthetic cellulose derivatives such as ethyl cellulose, cellulose acetate, hydroxyethyl cellulose, carboxymethyl cellulose and cellulose nitrate; polymers of unsaturated materials, such as acrylic acid ester polymers, methacrylate polymers, polyvinyl compounds, polystyrene; fats, oils and soaps; aromatic amines, dienes, terpenes and other naval stores. The statements as to properties and proportions as discussed hereinbefore in connection with cracked gasoline apply here as well.

Illustrating the general applicability of the subject inhibitors, the following examples are presented:

EXAMPLE III

A leaded aviation gasoline was tested for stability as described in Example 1, above. It had an induction period of 15 minutes. Two samples of this gasoline were inhibited with 1 and 2 mg. 3,5,3',5'-tetramethyl-4,4'-dihydroxydiphenyl of gasoline per 100 cc. respectively, and then tested for stability. The samples had induction periods of 400 and 470 minutes.

EXAMPLE IV

A highly refined white oil was tested for stability by the standard oxygen absorption test, oxygen being bubbled through the oil at 150° C. The times required to absorb oxygen both in the presence and in the absence of inhibitors are given in Table 3, below:

Table 3

Inhibitor	Time to absorb 250 cc. oxygen, hours	Time to absorb 750 cc. oxygen, hours	Time to absorb 1500 cc. oxygen, hours
None	0.3	0.8	1.8
3,3'-dimethyl-5,5'-di-tert-butyl-4,4'-dihydroxydiphenyl	29.6	31.0	34.1
3,3'-5,5'-tetramethyl-4,4'-dihydroxydiphenyl	17.3	17.6	18.0

We claim as our invention:

1. A stable cracked gasoline composition com-

6

prising cracked gasoline and from about 0.001% to about 0.1% by weight of 3,5,3',5'-tetramethyl-4,4'-dihydroxydiphenyl.

2. A cracked gasoline stabilized by the addition thereto of a small amount of 3,3'-dimethyl-5,5'-di-tert-butyl-4,4'-dihydroxydiphenyl.

3. A cracked gasoline stabilized by the addition

thereto of a small amount of 3,3'-diethyl-5,5'-di-tert-butyl-4,4'-dihydroxydiphenyl.

25 4. A cracked gasoline stabilized by the addition thereto of an alkylated dihydroxydiphenyl having the general formula

wherein each R1 is a primary alkyl radical, all of said radicals being identical.

35 5. A cracked gasoline stabilized by the addition thereto of an alkylated dihydroxydiphenyl having the general formula

45 wherein the R1's are identical primary alkyl radicals and the R2's are identical alkyl radicals differing from the R1's.

6. A cracked gasoline stabilized by the addition thereto of an alkylated dihydroxydiphenyl 50 having the general formula

55 wherein the R1's are identical primary alkyl radicals and R2's are identical alkyl radicals differing from the R1's.

60 7. A cracked gasoline stabilized by the addition thereto of a minor amount of a 3,5,3',5'-tetra-alkyl-4,4'-dihydroxydiphenyl wherein each alkyl

radical is a primary alkyl radical having from one to twelve carbon atoms.

8. A cracked gasoline stabilized by the addition thereto of a minor amount of a 3,5,3',5'-tetraalkyl-4,4'-dihydroxydiphenyl wherein each phenyl radical bears at least one alkyl radical selected from the group consisting of primary alkyl radicals and secondary alkyl radicals.

9. A liquid petroleum hydrocarbon stabilized by the addition thereto of a minor amount of a 3,5,3',5'-tetraalkyl-4,4'-dihydroxydiphenyl wherein each phenyl radical bears at least one alkyl radical selected from the group consisting of primary alkyl radicals and secondary alkyl radicals.

10. An unsaturated liquid hydrocarbon stabilized by the addition thereto of a minor amount of a 3,5,3',5'-tetraalkyl-4,4'-dihydroxydiphenyl wherein each phenyl radical bears at least one alkyl radical selected from the group consisting of primary alkyl radicals and secondary alkyl radicals.

11. An unsaturated liquid hydrocarbon tending to oxidize and form gummy substances stabilized by the addition thereto of a minor amount

5 of a 3,5,3',5'-tetraalkyl-4,4'-dihydroxydiphenyl wherein each phenyl radical bears at least one alkyl radical selected from the group consisting of primary alkyl radicals and secondary alkyl radicals.

12. A leaded aviation gasoline stabilized by the addition thereto of a small amount of 3,5,3',5'-tetramethyl-4,4'-dihydroxydiphenyl.

10 13. A highly refined white oil stabilized by the addition thereto of a small amount of 3,3'-dimethyl-5,5'-di-tert-butyl-4,4'-dihydroxydiphenyl.
